[57] CLAIM

The ornamental design for a combined toothpaste dispensing toothbrush and case therefor, as shown and described.

DESCRIPTION

FIG. 1 is a side elevational view of a combined toothpaste dispensing toothbrush, and case therefor showing my new design;

FIG. 2 is a top plan view thereof.

FIG. 3 is a bottom plan view thereof.

FIG. 4 is a cross-sectional view thereof, taken along line 4—4 of FIG. 3;

FIG. 5 is an exploded perspective view thereof;

FIG. 6 is a perspective view of the case.
